UNITED STATES PATENT OFFICE.

BENJAMIN NATHAN, OF NEW YORK, N. Y.

INNERSOLE.

No. 873,775.

Specification of Letters Patent.

Patented Dec. 17, 1907.

Application filed November 27, 1905. Serial No. 289,188.

To all whom it may concern:

Be it known that I, BENJAMIN NATHAN, a citizen of the United States, residing at New York, in the county of New York and State 5 of New York, have invented certain new and useful Improvements in Innersoles, of which the following is a specification.

My invention relates to inner soles for boots, shoes and similar foot wear and its 10 novelty consists in the construction and adaptation of the parts as will be more fully hereinafter pointed out.

It frequently happens that a person has a foot of such shape that it does not accurately 15 fit within a shoe of standard form and in order to insure the greatest amount of comfort to the wearer, the sole of the shoe should be built up or depressed at certain places. It also happens with almost every wearer of 20 shoes that there exists a tendency to turn certain portions of the foot in or out of the proper line in walking and the result is that the sole of the shoe receives greater wear at some places than at others.

25 The present invention aims to provide a means which will correct such tendencies to incorrect walking, and which is readily adaptable to the various needs or peculiarities of individuals. This object, and others 30 which will hereinafter appear, are accomplished by the construction illustrated in the accompanying drawing, which represents what is at present regarded as the best embodiment of the several important features 35 of the present invention.

In such drawings, Figure 1 is a top plan view of an inner sole embodying my several improvements, indicating in dotted lines the 40 positions of inserts or filling members. Fig. 2 is a bottom plan view of the same. Fig. 3 is an edge view thereof. Fig. 4 is a transverse section on the plane of the line 4—4 in Fig. 1. Fig. 5 is a transverse section on the plane of the line 5—5 in Fig. 1. Fig. 6 is a 45 similar section on the plane of the line 6—6 in Fig. 1. Figs. 7, 8 and 9 are perspective views of the inserts or filling members shown in the other figures: and Fig. 10 is a vertical central section through a low cut shoe inside 50 of which one of my improved inner soles has been placed.

The inner sole, in the form herein illustrated, comprises an upper layer 10 and a lower layer 20, each of which is made of 55 some suitable soft fabric, as thin leather, cloth, or rubber. In the form which I pre-

fer, the lower layer is made of thin leather, and the upper layer is made of two superimposed materials, one (as 11) of soft elastic character, for example sponge rubber, and 60 the uppermost 12 of soft, smooth character, as kid or paper. The lower layer 20 and the intermediate layer 11, in the form herein shown, are stitched together. The stitching is arranged to provide between them a series 65 of separated pockets (as 40, 60 and 60) having open marginal edges, adapted to receive removable inserts or filling members 41, 42 and 43, as hereinafter more particularly described, whereby the insole may be built up 70 at one or more places to give to the foot support at a place or places which the peculiarity of the individual wearer may make necessary in order to correct a tendency to improper walk and prevent unequal wear on the sides 75 of the sole or heel. Attention however is here called to the fact that the relation of the parts in the form herein shown is such that the layers lie smoothly one upon the other when said inserts or filling members are 80 omitted or removed, and the insole is, therefore, adapted to be worn with comfort, without an insert or filling member, by one whose needs do not call for such insert or filling member. By providing said insole with 85 open pockets adapted to receive removable filling members or inserts, and by so arranging said pockets that an insert may be placed at any one or more of the places which the different peculiarities of different individuals 90 make necessary, the range of usefulness of the device is widely extended, and in fact, it may be made to answer every requirement of all individuals, those whose walk is such that unless corrected they "run down" the 95 heel, or one side of the sole more than another, without restriction as to which side the extra wear may be on, as well as to those persons whose walk is normal or proper. Moreover, the adjustment to the needs of 100 an individual user, may be instantaneously made by any person, requiring no tools or skill for the purpose.

Upon reference to the drawings, it will be seen that the pocket 40 is arranged at the 105 ball of the foot portion of the insole, and is produced by securing the layers together by lines of stitches 30 and 31 which converge toward each other from opposite sides of the insole, and by lines of stitches 110 32 and 32 which converge similarly toward each other from opposite sides of the insole.

The relation of these stitches, therefore, is such as to provide a pocket which narrows from each marginal edge of the insole toward the longitudinal center of the insole. Thus, 5 in effect, two, or a pair of wedge-shaped pockets 40 are formed, each open along a contiguous marginal edge of the insole, whereby a correspondingly wedge-shaped insert or filling member, as 41, may be inserted 10 thereinto from either side of the insole and will be properly held in position by the side walls of the pocket.

The pocket 50 is arranged under the instep and is similarly bounded at one end by 15 rows of stitches 33 and 34 which converge toward each other from the open marginal edges of the insole; and at the other end by similar converging rows of stitches 36 and 39: thus also forming, in effect, under the instep 20 or arch of the foot, two wedge shaped pockets, either of which is adapted to receive a removable correspondingly wedge-shaped insert or filling member, as 42.

The pocket 60 is shown as arranged under 25 the heel and is formed by the stitches 37 and 38 which converge from the lateral marginal edges of the insole, which edges together with the back of the insole are non-stitched. The heel can thus be built up at any side or place 30 by an insert or filling member, such as 43, adapted thereto.

It will be observed that the two pockets 40, 40 open into each other at about the longitudinal center of the insole, and that this 35 is true also of the other pairs of pockets. The filling members when inserted into their respective pockets, that is, from either side of the insole, will preferably extend from the marginal edge of the insole across the longitudinal center of the insole and hence will 40 extend partway into the other pocket. While it is preferable to have different filling members for the several pockets 40, 50 and 60, yet it will not be a departure from the spirit 45 of the invention, or the scope of the subjoined claims, to use the same filling member for the several pockets, if such be capable of serving a useful purpose in the several places at which such pockets are located.

50 It will not be imagined that the necessities of any particular wearer will require the use of inserts or filling members at more than one place at a time, but it will be observed that as herein embodied, the insole has provision 55 whereby it is adaptable to any peculiarity. For example, if the wearer has a tendency to throw his right foot forward and wear out the sole of his shoe at its outside front edge, and by the strain thus produced upon the foot 60 cause callous or corns to develop by inserting the insert or filling member 41 in the pocket from the corresponding side of the insole, the foot of the wearer is thrown toward the other side, the pressure upon the skin relieved and 65 the corn or callous soon caused to disappear.

Similarly if the tendency is such that the sole has greater wear imposed on its inside front edge, it can be corrected by placing the insert or filling member in the side of said pocket 40 opposite to that hereinbefore mentioned. 70 Again, if the wearer of a shoe finds that the arch of the foot needs an extra support, the insert 42 may be placed in the pocket 50, provided for that purpose, and at either side thereof, thus furnishing the support required. 75 In a similar manner, the wedge 43 may be inserted in the pocket 60 at the heel of the inner sole, from either side thereof. The location of these pockets in the forms of inner sole illustrated herein are merely suggestive. 80 It is obvious that by varying the position of the stitches employed to unite the lower and intermediate layers of the sole, pockets may be formed at any desired place along the edge 85 of the sole for the reception of an appropriate insert or filling member, and while I prefer the form herein illustrated, yet it is not to be understood that the invention in all respects is restricted thereto.

The inserts or filling members 41, 42 and 90 43 are not only wedge-shaped by reason of having converging lateral sides, but, as herein shown, their top and bottom surfaces also relatively approach each other toward the inner end; that is to say, they are suitably so 95 formed as to be thinner as well as narrower at their inner than at their outer ends. In use, each will preferably extend to or slightly beyond the longitudinal center of the inner sole. These inserts or filling members are 100 preferably made of soft rubber, felt, cork, or some similar soft elastic material. They also preferably are of no great thickness whereby, in connection with their removability from the pockets, the layers of the insole may be 105 approximately of the same size and thus lie smoothly upon each other when the inserts or filling members are removed; thus adapting the insole for use without the inserts.

Having thus described the invention what 110 I believe to be new and desire to secure by Letters Patent, is:

1. An inner sole comprising a plurality of layers secured together and having between the same a substantially wedge shaped 115 pocket which is open along the contiguous marginal edge of the inner sole, and a removable substantially wedge-shaped filling member for said pocket.

2. An inner sole comprising a plurality of layers secured together and having between the same a plurality of pockets which are open at the opposite marginal edges of the inner sole and are narrowed toward the longitudinal center of the same, and a removable substantially wedge shaped filling member which is adapted to either of said pockets.

3. An inner sole, comprising a plurality of layers transversely stitched together, said stitches comprising a plurality of pairs of 130

lines which converge from the marginal edge of the inner sole toward the longitudinal center of the same so as to form a plurality of wedge shaped pockets which are open at the 5 opposite marginal edges of the inner sole and open into each other between said edges, and a removable wedge adapted to either of said pockets.

4. An inner sole comprising a plurality of 10 layers connected with each other by a series of rows of transversely extending stitches each having converging diagonal lines, said lines relatively arranged to form a plurality of separate pockets at each side of the longitudinal center of the insole, and each of 15 which is narrowed toward said center, and removable wedge-shaped filling members for said pockets.

5. An inner sole, comprising a plurality of 20 layers stitched together to form separate pockets which are arranged along the length of the insole and are open along the marginal edges of the latter, said stitches extending in a series of lines, some of which converge to 25 ward the longitudinal center of the insole from opposite sides thereof and are arranged at the ball portion of the insole, others of which similarly converge at opposite sides of the longitudinal center of the instep portion 30 of the insole, and others of which extend from one to the other marginal edge of the heel portion of the insole, and removable filling members for said pockets.

6. An inner sole comprising a plurality of 35 layers secured together and provided between said layers with a pocket which is open along the marginal edge of the insole, and a removable filling member which is adapted to said pocket and is thicker at its outer than 40 at its inner edge.

7. An inner sole comprising a plurality of layers secured together and provided between said layers with a pocket which is open along the marginal edge of the insole and narrows thence toward the longitudinal cen- 45

ter of the insole, and a removable substantially wedge shaped filling member which is adapted to said pocket, said filling member being thicker at its outer than at its inner edge and narrower at its inner edge than at 50 its outer edge.

8. An inner sole comprising an upper layer, a lower layer and an intermediate layer, said intermediate layer formed of yieldable material and secured at intervals to one of the other layers to form between them a pocket which is open along the marginal edge of the insole, and a removable wedge-shaped filling member adapted to said pocket. 55

9. An inner sole comprising an upper layer, 60 a lower layer and an intermediate layer, said intermediate layer formed of yieldable material and secured at intervals to one of the other layers to form between them a pocket which is open along the marginal edge of 65 the insole, and a removable filling member adapted to said pocket and thicker at its outer than its inner edge.

10. An inner sole comprising an upper layer and an intermediate layer, said intermediate layer formed of yieldable material and secured at intervals to one of the other layers by converging diagonal lines of stitches which are relatively arranged to form a plurality of pockets which are open 75 along the contiguous edges of the insole and narrow thence toward the longitudinal center of the insole and have open inner ends contiguous to each other, and a removable correspondingly narrowing filling member 80 which is adapted to either of said pockets and is thicker at its outer than at its inner edge. 70

In testimony whereof I affix my signature in presence of two witnesses.

BENJAMIN NATHAN.
